PHONOGRAPH

Richard M. Somers, West Orange, N. J., assignor
to Thomas A. Edison, Incorporated, West
Orange, N. J., a corporation of New Jersey

Application February 17, 1939, Serial No. 256,849

15 Claims. (Cl. 274—17)

This invention relates to phonographs, and has especial utility in connection with phonographs of the type by which there may be recorded, or selectively recorded and reproduced, sounds such as dictation and the like. In many of its aspects the invention concerns phonographs wherein there is employed, in suitable relationship to each record, an index blank whereon the operator may make, in appropriate relationship to the record, 10 annotations such as of points of error, of limits of dictation sequences, and the like.

In my co-pending application Serial No. 239,055, filed November 5, 1938, I disclosed the automatic performance of various functions upon index blank manipulation—i. e., upon insertion of the blank into, and its removal from, its holder in the phonograph. It is an object of the instant invention to cause the automatic performance of other useful functions upon index blank manipulation, or change of blanks in the holder.

It is an object properly to relate to each other the automatic performances of a plurality of functions occurring upon index blank manipulation.

It is an object properly to limit the automatic performance of certain functions upon manipulation of the index blank.

It is an object to eject the record from its support in the phonograph automatically at desirable times, without entailing undesirable ejections thereof at other times.

It is an object to provide improved automatic means for ejecting the record from its support.

It is an object to provide, in a phonograph having record ejecting means, an improved control of the ejecting function.

It is an object to provide, in a phonograph having a free-ended mandrel and an ejecting control at the free mandrel end, a simple remote control of the ejecting function.

Other and allied objects will more fully appear from the following description and the appended claims.

In the description reference is had to the accompanying drawings, in which:

Figure 1 is a plan view of the principal portions of a phonograph in which my invention has been embodied;

Figure 2 is a vertical cross-sectional view taken substantially along the line 2—2 of Figure 1;

Figure 3 is a partial vertical cross-sectional view taken substantially along the line 3—3 of Figure 1;

Figure 4 is a fragmentary, nearly vertical cross-

sectional view taken substantially along the line 4—4 of Figure 2;

Figure 5 is a partial, nearly vertical cross-sectional view taken substantially along the line 5—5 of Figure 2;

Figure 6 is a partial, nearly horizontal cross-sectional view taken substantially along the line 6—6 of Figure 5; and

Figure 7 is a schematic electrical diagram of the circuits of the phonograph immediately associated with my invention.

The phonograph in which my invention has been embodied may be generally described with reference first to Figures 1, 2 and 3. It includes a cast base plate 1 having a forward portion 1" which is generally horizontal but which curves upwardly at its rear 1a to join a raised horizontal rearward portion 1', as best seen in Figure 2. This base plate may be provided with the downward flange 1b around its periphery (as seen in Figure 2), and along its rear edge may be hinged to a lower enclosure 2, the front of the base plate normally resting on a bracket 2a extending inwardly from the front of that enclosure. Extending upwardly from the base plate 1 are the lefthand and righthand standards 5 and 6, respectively, and the intermediate standard 7, these standards serving to support various elements of the phonograph as hereinafter appears.

Journalled in a suitable bearing in the standard 7 is a mandrel shaft 9 on which, to the right of that standard, is carried a record support in the form of a generally cylindrical mandrel 10. This mandrel, best seen in Figure 3, may for example be in general of the form illustrated and described in U. S. Patent No. 2,010,717, issued August 6, 1935, on application of H. F. M. Gramann. For present purposes it may be briefly described as follows:

Within the standard 7 is disposed the left-hand end portion 307 of a stationary sleeve 304, the sleeve being provided with a flange 303 securing it to the right-hand side of the standard 7, and extending rightwardly to near the right-hand end of the mandrel. The shaft 9 extends through the sleeve 304, the sleeve portion 307 forming a left-hand bearing for that shaft, and means (as in the mentioned patent) being provided at the right-hand end of the sleeve to form a right-hand bearing for the shaft within the sleeve. Outside the sleeve, and extending rightwardly from the standard 7, there is provided a hollow shaft 309 whose end portions bear on the sleeve; and at their right-hand extremities the inner 50 55 60 65 and outer shafts 9 and 309 are appropriately secured together for joint rotation, a portion of the securing means appearing as the nut 310.

Around the outer shaft 309 throughout most of its length there is supported, as by discs 321 and 322, a hollow, substantially cylindrical but slightly tapered shell 320 which serves as a guide for the mounting of a cylindrical record on the mandrel. At the right-hand, smaller end of shell 10 320 is a hollow conical chuck 327 having a plurality of sections or jaws 328. The smaller end of the chuck, or left-hand ends of the sections, are loosely connected to a supporting collar 331 secured on the outer shaft 309 within the shell 320; 15 the larger end portion of the chuck extends outwardly of the shell, and is shouldered so as to provide an enlarged conical bearing portion 333 for engagement with the smaller end of the bore of a record mounted on the mandrel. The outer 20 ends of the chuck sections 328 are provided with inwardly extending flanges which, by a coiled spring 330 encircling the chuck sections 328, are held in abutment against the rightwardly convergent conical surface of a knob 335. A leftward or 25 inward extension 336 of this knob is slidably mounted on the outer shaft 309, its movement longitudinal of the shaft being limited as by a screw 340 passing through a slot 339 in the knob extension; and the knob is biased to rightward 30 movement, to expand the chuck 327, by a spring 341 disposed within the knob and compressed between its inner end surface and the nut 310.

To the left of the shell 320 there is slidably mounted on the outer shaft 309 a record supporting and ejecting disc or head 352, formed with an outwardly extending flange 353 and a rightwardly extending, tapered annular flange 354 adapted to engage the larger end of the bore of a record mounted on the mandrel. The head 40 352 is also provided with a long integral sleeve 355 extending rightwardly about the shaft 309 to within the shell 320, and carrying an outwardly extending flange 356 at its right-hand end; rightward movement of the head 352 is limited by the 45 impingement of the flange 356 against the shell-supporting disc 321 above mentioned, preferably through the intermediary of a washer 321' of felt or other shock-absorbing material. Secured in and extending leftwardly from the disc 321 and 50 freely through the flange 356 are a plurality of rods headed at their left-hand extremities, one of these rods appearing as 361; and between the head of each rod and the flange 356 there is compressed a respective spring such as 359, the 55 springs serving to bias the head 352 rightwardly.

At the left-hand extremity of the knob extension 336 there is provided an outwardly extending lip 338; and to engage this lip there is provided a pawl 343, pivotally mounted on a pin 344 carried by a leftward extension 345 of collar 331, and freely extending through the chuck 327 to bring its extremity adjacent the lip. The pawl is biased clockwise (when viewed in the direction of Figure 3), to bring its extremity radially inwardly sufficiently to engage the lip, by a rod 347 connected with the pawl and passing freely through the discs 322 and 321, and a spring 346 encircling the rod to the right of disc 321 and compressed between that disc and a washer 350 retained on the rod by a crosspin 351. The rod 60 347 extends leftwardly through flange 356, and to the left of this flange is provided with an adjustable nut 363 which may be moved by the flange.

75 When a record R is mounted on the mandrel,

as indicated by the dash-dot lines in Figure 3, the record holds the head 352 in a leftwardly displaced position from that to which it is biased; flange 356, likewise displaced, holds pawl 343 out of engagement with lip 338; and knob 335 is subjected to its rightward bias, so that the chuck 327 is expanded to internally grip the right-hand end of the record and, through the record, to maintain head 352 in the displaced position. Leftward movement of the knob 335, however, will cause the contraction of the chuck 327, whereupon the bias of the head 352 will move the head rightwardly and thus effect rightward, or ejecting, movement of the record. At the same time the rod 347 will be permitted to move rightwardly 10 in obedience to its bias, moving the pawl 343 into lip-engaging position and, assuming sufficient knob movement, actually causing engagement of the lip 338; this lip engagement will hold the knob 335 leftwardly displaced, and thus the chuck 20 members contracted, until another record is mounted on the mandrel. The leftward movement of head 352 by a record in the final portion of its movement onto the mandrel serves to disengage the pawl 343 from the lip 338, whereupon 25 knob 335 is permitted to obey its bias and expand the chuck to establish the conditions illustrated and assumed at the beginning of this paragraph.

While the construction and operation of the mandrel has been illustrated and described in considerable detail, reference may if desired be had to the mentioned patent for further details.

The mandrel shaft 9 extends to the left of standard 7 toward a driving pulley 11 rotatably mounted at the right of standard 5, the pulley 35 11 being rotated as by a belt and motor not herein necessary to show. Secured to the pulley 11, and splined on the end portion of the shaft 9, are the respective elements 18 and 19 of a clutch 20. The element 19 is provided with an annular groove 19', in which there is positioned a pin 21 secured in the upper extremity of a clutch-operating arm 22; the arm position is controlled by a start-and-stop device, not herein necessary to show, to shift the element 19 selectively into and out of engagement with the element 18, and so to engage and disengage the clutch to cause and stop rotation of the mandrel by the pulley 11.

Above and behind the mandrel there extend, between the standards 5 and 6, the respective 50 carriage rods 23 and 24, along which there is slidable a carriage 40. The carriage extends forwardly over the mandrel, and carries in its forward portion a translating device 30 arranged for co-operation with a record R on the mandrel. The carriage may be driven rightwardly along the rods 23 and 24 by a feed screw 25, journaled between standards 5 and 6 behind the rod 23, and engageable by a feed nut 27 carried in the carriage. The feed screw 25 may be rotated, by 60 a train of gears 26 coupling it rotationally with the mandrel shaft 9, coincidentally with mandrel rotation.

It will be understood that the mandrel 10 and the carriage 40 form a system for producing 65 translation-effecting relative movement between the record R and the translating device 30—e. g., a movement which causes either of the translating device styls (hereinafter mentioned) to traverse a spiral path on the record, for the translation of oscillatory energy into a recording on the record or vice versa. And while the described translation-effecting movement is the movement appropriate to the type of record and type of phonograph which I have chosen for illustrative 70 75

purposes, I intend no unnecessary limitation of the broader aspects of the invention to those types or to the particular nature of that movement.

5 While the translating device 30 may in recordation be actuated by, and may in reproduction produce, oscillatory energy of any of a wide variety of natures, I have shown it as provided with an upwardly extending neck 29, to which a sound-
10 conveying tube (not shown) may be attached for the conveyance of sound to and from the translating device. The translating device which has been chosen for illustrative purposes is a sound box, in general of the form shown and
15 described in U. S. Patent No. 1,989,198, issued January 29, 1935, on application of Charles Heunlich, to which reference may be had for typical details; for present purposes it is sufficient to note only a few of the components of the translating device. It may include two members movably mounted in its lower part, the upper of these members being designated as 31 and the lower as 32. When both members are free of upward restraint, a smooth ball 34 attached to member
20 32 contacts the record surface, without effect on the latter, and a recording stylus 35 carried by the upper member 31 also contacts the record surface; the translating device is then conditioned for recordation on the record—e. g., for
25 30 the engraving in the record surface of a groove of depth undulating in accordance with sound energy supplied to the device through the neck 29. When the upper member 31 only is held upwardly, both the ball 34 and the recording stylus 35 are held away from the record, and a reproducing stylus 36, suitably carried by the member 32, is brought into contact with the record surface; the translating device is then conditioned for reproduction from the record—e. g.,
35 40 for the emission through the neck 29 of sound energy translated by the device from an undulating record groove being traversed by the reproducing stylus 36. When both members 31 and 32 are held upwardly, the ball 34 and both the stylus 35 and 36 are held away from the record; the translating device is then in neutral condition.

The carriage 40 is provided with a horizontal sleeve 43 secured between the sides of the carriage and extending for a distance leftwardly
50 from the left-hand side, this sleeve slidably surrounding the rod 23 and forming a long bearing for the carriage on that rod. The means for variously positioning the members 31 and 32, and thus for selectively conditioning the translating device, comprises a member 60 rotatably surrounding this sleeve 43 within the carriage; a mechanism (for example such as is shown in my co-pending application abovementioned), including lugs such as 38 on member 32 and lifting fingers such as 46 co-operating therewith, but not necessary fully to detail herein, for rendering the positions of the members 31 and 32 responsive to the angular position of member 60 about the sleeve 43; and a plurality of means
55 60 for controlling that angular position.

That one of those means which is available for manipulation by the hand of the operator of the phonograph may be mentioned as a control lever 39, pivoted on a horizontal stud 39' at the
70 righthand side of the carriage, and extending forwardly from that stud. A stud 69 is extended rightwardly from a lower portion of the member 60, through an arcuate aperture 42' in the righthand side of the carriage; and a link 70 is pivotally secured to this stud, and extends forwardly
75

therefrom to have its forward extremity pivotally secured to the bottom of a short arm 39'' integral with and extending downwardly from the control lever 39.

For purposes hereinafter apparent there is provided, in addition to the manually operable lever 39, another lever to the position of which the angular position of the member 60 is responsive, and vice versa. This other lever appears as 72, being secured to member 60 and therefrom extending upwardly through an aperture 71 in the top of the carriage.

As illustrated in Figures 1 and 2, the control lever 39 is in its downmost position, lever 72 is in its most forward position, and member 60 is in its most counter-clockwise position (as viewed in the direction of Figure 2); both members 31 and 32 are free of upward restraint, and the translating device is conditioned for recordation. When the control lever 39 is in its upmost position, lever 72 is in its most rearward position, and member 60 in its most clockwise position (for example about 60 degrees displaced from its illustrated position), member 31 only is held upwardly and the translating device is conditioned for reproduction. When the control lever 39 and lever 72 and member 60 are all in their intermediate positions, both members 31 and 32 are held upwardly and the translating device is in a neutral condition.

It is desirable that the feed nut 27 be disengaged from the feed screw 25 throughout a neutral condition, but engaged therewith during either translation condition (i e., for recordation or reproduction), of the translating device. Accordingly the feed nut may be mounted, above the feed screw, on an arm 68 which forms a part of an integral arm system pivoted within the carriage as at 44, the other portions of which arm system include the upwardly extending arm 47' and the forwardly extending arm 65. The arm system is biased clockwise (as viewed in the direction of Figure 2), for engagement of the feed nut with the feed screw, by a strong spring 66 tensioned between the top of arm 47' and a cross rod 55 provided in the rear top portion of the carriage. The arm 65 extends underneath a roller 56 carried on a horizontal pin 59 secured to member 60; and the top of arm 65 is provided with a high centrally indented portion 65''. When the translating device is in recordation condition the roller 56 is behind, and when the device is in reproduction condition the roller is in front of, the center of portion 65''; but as the member 60 is moved into its intermediate position for neutral translating device adjustment, the roller 56 is moved onto the high central portion 65'', forcing a slight counterclockwise rotation of arms 65—47'—68 and so a disengagement of the feed nut—the indentation of 65'' serving if desired as a detent for the neutral translating device adjustment.

It is common, in phonographs of the general type described, to employ with each record an individual "index" blank, for example in the form of a slip, which is inserted in appropriate position in the phonograph and upon or in which there may be made annotations indicating points of error and/or correction in the recordation, lengths of dictation sequences, and the like—the slip being removed with the record and employed in later transcription from that record for the guidance of the transcriber. In the figures there has been shown a holder 80 for such an index slip, disposed just above the front of the base plate 75

below and forward of the mandrel 10. The holder may consist of a slightly inclined flat plate having folded-over front and back flanges 79, and held to the front flange 1b of the base plate by a long bracket 78. At the front corners of the base plate 1, to the left and right of the holder 80, the base plate may be formed upwardly into the inclined surfaces 75 and 76 substantially aligned with the holder; an index slip S may be slid leftwardly over the surface 76 into the holder 80, the left-hand portion of the surface 76 being desirably provided with an indentation 77 for the accommodation of the finger in the manipulation of the slip. While any means for relating points in the recording to points on the index slip may be employed, I have illustrated a simple pointer 74 extending downwardly from the front of the carriage 40 and then forwardly over the index slip; this pointer, travelling longitudinally of the slip in accordance with the travel of the translating device longitudinally of the record, may be employed as a guide for pencil marks or the like on the slip.

In my co-pending application abovementioned I disclosed the performance of various functions—e. g., carriage return to initial (left-hand) position, placement of the translating device in neutral condition, etc.—by the act of removal of an index blank from its holder, and the performance of other functions—e. g., placement of the translating device in a predetermined translating condition—by the act of index blank insertion into its holder. According to the instant invention I perform, by the act of index blank removal, another function—the ejection of the record from its support, or mandrel 10. In carrying out the instant invention I may retain any or all of the functions of the index blank manipulation abovementioned; as an example, and for the particular purpose of insuring the freedom of any portion of the translating device (e. g., the styli) from contact with the record at the time of record ejection, I have particularly illustrated herein the placement of the translating device in neutral condition by the blank removal. The means for performing this function may be first described, it may, though non-limitatively, be generally similar to that disclosed for this function in my co-pending application, and in that event is electrically controlled by a switch in suitable association with the slip holder 80.

This switch may be contained within a housing 81, for example molded of insulating material, seen in position in the phonograph in Figure 1 and illustrated in vertical cross-section in Figure 4. The right-hand portion of this housing is disposed within an aperture 80a cut into the left-hand end of the holder 80, while the left-hand portion of the housing may extend into a slot 75a cut into the inclined surface 75 of the base plate 1. The housing may comprise a generally rectangular box, of the vertical dimension of which about half is disposed above and half below the plane of the index slip S (the term "vertical" being here employed to denote right-angularity to the slightly inclined plane of the slip); and in this plane the housing may be provided with a slot 84 leading leftwardly from the right-hand housing extremity for about half the length of the housing—the slot 84 serving to admit the slip, and its left-hand extremity serving to define the fully inserted position of the slip. The housing is desirably provided with a cover 89 of insulating material.

75 In the housing 81 is provided the closely biased

switch 85 comprising a pair of leaf springs 86 having left-hand terminal portions held in an insulating stack 85a, and extending rightwardly therefrom respectively above and below the plane of the slip S. Near their right-hand extremities 5 the springs are bent to touch each other in the absence of the slip; but they are provided at their extremities with the divergent cam portions 86'. A slip S, impinging on these cam portions during its insertion, forces the springs apart and passes 10 therebetween, thereby (in view of the insulating nature of the slip material) effectively opening the switch 85 and holding it open so long as the slip remains inserted.

For automatically placing the translating device in neutral condition by the removal of the slip S, I connect, across the power supply for the phonograph, a circuit serially comprising the closely biased switch 85 and a solenoid system 140 which, when energized under a condition of the 20 translating device for either recordation or reproduction, will immediately place the translating device in neutral condition—the solenoid system simultaneously open-circuiting itself so that, among other things, wasteful continued current 25 flow therein will be avoided. The described electrical arrangement is illustrated in the schematic Figure 7, wherein the terminals 121 and 122 represent the mentioned power supply; the switch 85 appears in this figure in open condition, with 30 the slip S between its springs 86. The electrical features of the solenoid system 140, shown in Figure 7, are best understood following a mechanical description of that system, for which reference may be had to Figures 1 and 2.

The system 140 comprises a coil 141 having a front-and-back extending axis; a rectangular frame 142 of magnetic material surrounding and supporting the coil, mounted on a horizontal platform 143 which extends rearwardly from the 40 relatively high central carriage portion above the relatively lower rear carriage portion, and apertured axially of the coil; a magnetic plunger 144 movable axially of the coil therewithin; and a switch assembly 145 secured behind the frame 45 142 and operated by the plunger 144, the casing 145a of the switch assembly appearing in Figures 1 and 2. The forward end of the plunger is bifurcated, and to it is pivotally connected the rear extremity of a rod 72a; to the forward 50 extremity of this rod is adjustably secured a U-shaped member 72b, which is pivotally connected to the top of the lever 72 abovementioned. Thus the position of the plunger axially of the coil corresponds with the condition of the translating device, being forward for a recordation condition, intermediate for a neutral condition, and rearward for a reproduction condition. The components are apportioned and adjusted so that the intermediate plunger position will be the one 55 wherein it is longitudinally centered or symmetrically disposed with respect to the coil 141.

As seen in the electrical showing of Figure 7, the switch assembly 145 comprises a pole 146 moved by the plunger, a pair of contacts 65 147a—147b connected together by the pole 146 when the plunger is in forward position, and a pair of contacts 148a—148b connected together by the pole 146 when the plunger is in rearward position. Contacts 147a and 148a are connected 70 together to form one electrical side, and contacts 147b and 148b are connected together to form the other electrical side, of the switch assembly 145, and this is electrically placed in series with the coil 141. Thus when the lever 72 is vertically 75

disposed, the translating device in neutral condition, and the plunger 144 axially centralized within the coil 141, the switch assembly 145 serves to maintain the coil open-circuited so that it cannot be energized. But if the translating device be in either recordation or reproduction condition, and the plunger 144 thus decentralized forwardly (as in Figure 7) or rearwardly with respect to the coil 141, that coil will not be open-circuited at the switch assembly 145; then if the switch 85 be closed by removal of the index slip, the coil 141 will be energized to move the plunger 144 into centralized position, placing the translating device in neutral condition and open-circuiting the coil. And so long as no slip is in the holder and the switch 85 therefore remains closed, any attempt to place the translating device into recordation or reproduction condition will, in view of its re-closing of the coil circuit at the switch assembly 145, be followed by an immediate restoration to neutral condition. Of course upon re-insertion of a slip in the holder 80, the switch 85 will be opened, rendering the solenoid system 140 ineffective and restoring the free adjustability of the translating device.

For automatically ejecting the record by the removal of the slip S, I connect another circuit across the power supply, or terminals 121—122, as seen in Figure 7. This circuit serially comprises a switch assembly 240 hereinafter described, and an electromagnet 270 which, when momentarily energized, imparts a momentary leftward movement to the mandrel knob 335 above described—this movement causing record ejection from the mandrel, and the latching of the knob in leftwardly displaced position to maintain the mandrel ready for the mounting of another record, both as described above. The electromagnet 270 and its operative connection with the mandrel knob, best seen in Figure 3, may be first described.

The electromagnet may comprise a side-to-side extending core 271, a coil 272 surrounding the core, and a U-shaped frame 273 of magnetic material extending above and at the right of and below the coil, the righthand extremity of the core 271 being secured to the central portion of the U. The frame 273 may be secured to the bottom of a bracket 274 bridged across the bottom of an aperture 1c which is provided in the base plate 1 underneath the pulley 17. At the lefthand or open extremity of the U-shaped frame 273 there is provided an armature 276 of magnetic material, resiliently held normally in spaced relationship to the left-hand extremities of the frame and core by a suitably formed leaf spring 275 secured to the armature and to the bottom of the frame; it will of course be understood that upon energization of the coil 272 the armature 276 will be attracted rightwardly into at least substantial contact with the frame and core extremities. A pair of vertical ears 277 are folded leftwardly from the top portion of the armature 276, and between these ears is secured a horizontal pin 278. This pin passes rotatably through the lower end portion of a lever 280, an intermediate portion of which lever is pivoted on a horizontal pin 279 secured between two ears 5a extending leftwardly from the standard 5 below the axis of the mandrel; the lever extends upwardly at the left of standard 5 to have its top end portion opposite the axis of the mandrel and of pulley 17.

As seen in Figure 3, the pulley 17 is rotatably

mounted on a shouldered cylinder 17a whose left-hand extremity is secured in the standard 5. This cylinder, which is in alignment with the mandrel shaft 9, is of course centrally hollow, and that shaft is likewise made hollow; and through both cylinder and shaft there freely extends a horizontal rod 281, the rod serving to couple the knob 335 with the lever 280. At least one end of the rod must be rotationally free, and I prefer that both ends be rotationally free, of those respective elements which the rod couples. Thus the rod may pass through a hole 335a in the end of knob 335, this hole forming a rotary bearing for the right-hand rod extremity; the outer or right-hand portion of this hole may be enlarged into the recess 335b, and in this recess the rod may be provided with a head 283 which, when the rod is leftwardly pulled, bears on the shoulder 335c between the two hole portions. In its other end portion the rod 281 may pass through a hole 280a in the upper end portion of the lever 280, this hole forming a rotary bearing for the left-hand rod extremity; and nuts 282 may be adjustably secured on the rod immediately to the left of the lever, preferably so that the rod is just free of longitudinal play when the mandrel 10 carries a record and knob 335 is therefore in its rightward position. It will be obvious that upon momentary energization of the electromagnet 270 and consequent momentary counterclockwise rocking of the lever 280, the upper end portion of the lever will move leftwardly the nuts 282 and the rod 281 with its head 283, and will accordingly move leftwardly the knob 335. The distances of movement of the various parts are so apportioned that this knob movement will be sufficient not only to eject the record but also to cause the above-mentioned latching of the knob in leftwardly displaced position. After lever 280 is restored (by spring 275) to its normal or illustrated position at the conclusion of the momentary electromagnet energization, and until the knob is restored rightwardly by subsequent record mounting, the rod 281 will have longitudinal play; and to prevent its head 283 from then protruding beyond the surface of knob 335 a thin plug 284 may be threaded into the knob recess 335b, though of course for a distance insufficient to bind the head 283 against the shoulder 335c.

The switch assembly 240 serves to control the energization of the electromagnet 270. The assembly includes a control member 241 moved to respective positions by the removal and by the insertion of a slip from and into the holder 80; but a feature of the assembly is that it functions to close the electromagnet circuit only momentarily (i. e., for an automatically restricted, very short time interval), and only as an incident of slip removal (and not also of slip insertion). The restriction to momentary closure is desirable not only to obviate wasteful current flow, but also so that if a record be mounted on the mandrel before the insertion of its accompanying slip (as is preferred according to my co-pending application abovementioned, and as in any event may frequently be done), that record may be properly seated on the mandrel and not subjected to immediate ejection. The restriction to closure only upon slip removal (and not also on insertion) is strongly preferred so that, among other things, a record mounted before accompanying slip insertion shall not be ejected upon that insertion. It may be noted that in the switch assembly illustrated for the performance of the so-limited

switching function I have embodied features disclosed and claimed in my co-pending application Serial No. 252,523 filed January 24, 1939, and entitled "Electric switching."

5 The switch assembly 240, illustrated in detail in Figures 2, 5 and 6, may be housed in a rectangular casing 242 of insulating material disposed (as seen in Figure 1) underneath the right-hand rear portion of the holder 80 and extending 10 downwardly therefrom through a suitable aperture 239 provided in the base plate 1. The base plate may have an inclined flange 238 folded downwardly along the front edge of this aperture, and to this flange may be secured a flat 15 member 243—the casing being secured behind this member by screws 244 passing through the member into the corners of the casing, the member 243 serving as a cover for the casing, and the top of the casing being at least substantially 20 in contact with the bottom of the holder 80. In the top of the casing, underneath the rear holder flange 79 and about centrally of the side-to-side casing dimension, there may be provided a rectangular aperture 242a; and above this aperture 25 there may be provided, in the holder 80 and its rear flange 79, corresponding apertures 80b and 79b respectively. The control member 241 for the switch assembly 240 is a short arm, pivoted on a horizontal screw 245 extending forwardly from the rear of the casing a little underneath the right-hand extremity of the aperture 242a. The free extremity of this arm is biased (as hereinafter appears) upwardly so that in the absence of a slip S from the holder 80 the arm 241 extremity extends diagonally upwardly through 30 apertures 242a and 80b toward flange 79, and preferably into the flange aperture 79b; as a slip S is inserted into the holder, however, the left-hand slip extremity will cam the arm 241 downwardly to the position illustrated in Figure 5, wherein the arm extremity bears against the bottom of the slip. It will be understood that the provision of the aperture 79b in the flange 79 and the extension of the arm 241 thereinto, 40 though not indispensable, are desirable to permit a reasonably wide throw of the arm by slip manipulation.

Integral with the arm 241 there may be provided an arm 246 extending diagonally leftwardly and downwardly, and to this arm may be secured an extension 247 of insulating material; the arm extension 247 is biased upwardly (and the arm 241 thus biased as abovementioned) by a spring 249 tensioned between a pin 247a carried by the arm extension and a pin 248 secured to the rear of the casing thereabove. At the free end of the arm extension 247 there is provided an electrical contact member 251; when no slip is in the holder 80 the bias of the arm extension 50 brings this contact member into contact with a spring 252 secured on and extending rightwardly from a lug 253 formed inwardly from the left-hand side of the casing—the member 251 and spring 252 forming a switch 250 which is closed as a slip is withdrawn from the holder and is opened as a slip is inserted thereinto. The spring 252 is relatively flexible, so that after contact of member 251 therewith, a considerable upward movement of arm extension 247 may still occur—for example to bring that arm extension into contact with a stop pin 254 extending forwardly 60 from the rear of the casing thereabove.

In series with and operated by the switch 250 is a momentary-contact switch 260. This switch 70 may include an arm 257 of insulating material,

pivoted at an intermediate point on a horizontal screw 255 extending forwardly from the rear of the casing, and held in a plane in front of that of the extension 247 by a bushing 255a surrounding the screw. Stop pins 256 may extend forwardly 5 from the rear of the casing above and below the arm 257, separated to allow a swing for the arm typically of the order of 25 or 30 degrees. The arm 257 may extend almost to the right-hand end of the casing, and at its right-hand extremity 10 carries an electrical contact member 258; and a stationary contact member 259 is secured to and extends forwardly from the rear of the casing in appropriate arrangement to be contacted by member 258 during the intermediate portion of 15 the swing of arm 257 from one stop pin to the other.

The switches 250 ad 260 are placed electrically in series as by a flexible conductor 268 connecting members 251 and 258, the spring 252 and stationary contact member 259 forming the electrical terminals of the switch assembly 240. The arm 257 is toggled to the arm extension 247 by a spring 261 tensioned between pins 262 and 263 extending forwardly from 247 and 257 respectively, the spring 261 being weak enough to avoid interference with the above described function of spring 249; and when a slip S is in the holder 80 and the arm extension 247 is thus held downwardly, arm 257 will be held by spring 261 against 30 the lower stop pin 256. The arrangement is such that when the slip, being withdrawn, clears the control arm 241 and the arm extension 247 thus moves upwardly in response to spring 249, member 251 will first touch spring 252 to close the 35 switch 250; almost immediately thereafter, during the continued movement of the arm extension 247 up to pin 254, the line of force of spring 261 will be brought sufficiently above the axis of screw 255 to throw the arm 257 upwardly against 40 the upper stop pin 256, thus momentarily closing the switch 260 after the closing of the switch 250, and imparting a momentary energization to the 45 electromagnet 270. Upon the downward movement of the arm 247 attendant on insertion of a 50 slip in the holder, however, the arm extension 247 will be moved downwardly sufficiently to open the switch 250 before the line of force of spring 261 is brought sufficiently below the axis of screw 255 to throw the arm 257 downwardly; thus the momentary closure of switch 260 upon 55 slip insertion occurs after switch 250 is opened and is therefore (in view of the serial connection of the switches) ineffective to energize the electromagnet 270.

In order that the momentary energization of the electromagnet 270 upon slip insertion may assuredly be of sufficient duration for the full leftward movement of knob 335 above described, the rate of motion of the arm 257 between its stop pins 256 may be appropriately adjusted—not only by a sufficiently weak tensioning of the spring 261, but also by the securing to the arm of one or more weights such as 265, which may be apportioned and arranged to substantially balance 65 the arm about its pivot.

While I have disclosed my invention in terms of a particular embodiment thereof, I do not intend that its broader aspects be limited by the details of that embodiment, which obviously may be widely varied without departure from the spirit of the invention. The proper scope of the invention I undertake to express in the following claims—in some of the claims broadly, subject 75

however to such proper limitations as the state of the art may impose.

I claim:

1. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; control means associated with said holding means and operated incidental to change of the index blank therein; and means, connected with and rendered effective by said control means, for ejecting the record from said supporting means.

2. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; control means operated by the index blank in its removal from said holding means; and means, controlled by said control means, for ejecting the record from said supporting means.

3. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; ejecting means operable to eject the record from said supporting means; and means, associated with said holding means and operated incidental to change of the index blank therein, for controlling the operation of said ejecting means.

4. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; electrically actuatable means for ejecting the record from said supporting means; and switch means, associated with said holding means and closed during removal of an index blank from said holding means, for controlling the operation of said ejecting means.

5. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; control means associated with said holding means and operated incidental to change of the index blank therein; and means, connected with said control means and rendered effective thereby only during removal of an index blank from said holding means, for ejecting the record from said supporting means.

6. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; means, operable by momentary impulse, for ejecting the record from said supporting means; and means for imparting a momentary impulse to said ejecting means only during removal of an index blank from said holding means, comprising a control member associated with said holding means and operatively connected with said ejecting means.

7. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; control means associated with said holding means and operated incidental to change of the index blank therein; means, operable by momentary impulse, for ejecting the record from said supporting means; and means, operatively connected with and controlled by said control means, for imparting a momentary impulse to said ejecting means.

8. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; means, operable by momentary electrical actuation, for ejecting the record from said supporting means; and switch means, associated with said holding means and subjected to momentary closure only during removal of an index blank from said holding means, for controlling the actuation of said ejecting means.

9. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; electrically actuatable means for ejecting the record from said supporting means; and a pair of switches controlling said ejecting means, a first of said switches being associated with said holding means and being thrown to open and closed conditions respectively by insertion and removal of an index blank into and from said holding means, and the other of said switches being momentarily closed upon each throw of said first switch.

10. In a phonograph including means for supporting a record, a translating device arranged for translation-effecting movement relative to the record, and means for indicating the position of said device relative to the record: the combination of holding means into and from which an index blank may be inserted and removed and

with which said indicating means is associated for cooperation with a blank held therein; electrically actuatable means for ejecting the record from said supporting means; and means controlling said ejecting means, comprising a control member moved to two respective positions by insertion and removal of an index blank in and from said holding means, and switch means including a switch arm toggled to said control member for operation thereby.

11. In a phonograph including means for supporting a record, a translating device arranged for translation-effecting movement, and selectively conditionable in neutral and translating conditions, relative to the record, and means for indicating the position of said device relative to the record: the combination of holding means into and from which an index blank may be inserted and removed and with which said indicating means is associated for cooperation with a blank held therein; first and second control means successively responsive to removal of an index blank from said holding means; means, rendered effective by said first control means, for placing said translating device in neutral condition; and means, rendered effective by said second control means, for ejecting the record from said support.

12. In a phonograph including means for supporting a record, a translating device arranged for translation-effecting movement, and selectively conditionable in neutral and translating conditions, relative to the record, and means for indicating the position of said device relative to the record: the combination of holding means into and from which an index blank may be inserted and removed and with which said indicating means is associated for cooperation with a blank held therein; two control means differently associated with said holding means for successive operation incidental to index blank removal from said holding means; and means for placing said translating device in neutral condition, and means for ejecting the record from said

support, said last recited two means being respectively controlled by said two control means.

13. In a phonograph including means for supporting a record, a translating device arranged for translation-effecting movement relative to the record, and means for indicating the position of said device relative to the record: the combination of holding means into and from which an index blank may be inserted and removed and with which said indicating means is associated for cooperation with a blank held therein; means for ejecting the record from said supporting means; an electric circuit closeable to actuate said ejecting means; and means connected in said circuit and controlling said ejecting means, comprising a switch momentarily closed by index blank insertion in and by index blank removal from said holding means, and switch means for maintaining said circuit open at the time of closure of said switch by index blank insertion. 20

14. In a phonograph: the combination of a record-supporting mandrel; a bearing in which said mandrel is journaled at one end thereof, said mandrel being free at its other end for mounting and removal of a record; means for ejecting a record from the mandrel, and control means at the free end of the mandrel movable to actuate said ejecting means; and means for remotely operating said control means, including a rod connected with said control means and passing axially through said mandrel and bearing. 25

15. In a phonograph: the combination of a record support; a holder, comprising substantially parallel and closely spaced members, in predetermined relationship to said support and adapted to admit an index blank between said members, at least a first of said members being provided with an aperture; means for ejecting a record from said support; and means for controlling said ejecting means, comprising a control member extending through said aperture toward, and biased to movement at least substantially as far as, the second said member. 35 40

RICHARD M. SOMERS.
